CLAIM

The ornamental design for a hand-grip with ring, as shown and described.

DESCRIPTION

FIG. 1 is a perspective view of a hand-grip with ring, embodying the new design;

FIG. 2 is a top view of the hand-grip with ring of FIG. 1; FIG. 3 is a bottom view of the hand-grip with ring of FIG. 1;

FIG. 4 is a front view of the hand-grip with ring of FIG. 1; FIG. 5 is a back view of the hand-grip with ring of FIG. 1; FIG. 6 is a left view of the hand-grip with ring of FIG. 1; and,

FIG. 7 is a right view of the hand-grip with ring of FIG. 1. The broken lines shown in the drawings are for illustrative purposes only and form no part of the claimed design.
